MULTIPLE GROOVED NAIL FILE

Maxwell A. West, Portland, Oreg.

Application June 11, 1949, Serial No. 98,517

1 Claim. (Cl. 132—76.4)

1

This invention relates generally to manicuring instruments and particularly to a universal nail file.

The main object of this invention is to produce a file having a plurality of nail cutting surfaces formed on a single piece of stainless steel.

The second object is to confine some of the cutting surfaces to grooves to prevent the file from running off the nail while being used.

The third object is to provide a file which will form a curved edge on a nail in order to prevent the usual feather edge which should be trimmed away.

The fourth object is to leave the back of the cutting portion smooth in order to prevent injury to the skin.

The fifth object is to provide a variety of grades of cutting surfaces, ranging from coarse to extra fine, on a single piece of metal.

The sixth object is to construct a file which, though flexible enough for its purpose, is also exceedingly rugged, owing to its shape, making possible the use of lighter gauge material than is otherwise used for such devices.

I accomplish these and other objects in the manner set forth in the following specification as illustrated in the accompanying drawing, in which:

Fig. 1 is a plan of the preferred form of the file.

Fig. 2 is a view of the file opposite the side shown in Fig. 1.

Fig. 3 is a side elevation.

Fig. 4 is a transverse section taken along the line 4—4 in Figs. 3 and 7.

Fig. 5 is a plan of a modified form of the file.

Fig. 6 is a view opposite to Fig. 5.

Fig. 7 is a side elevation of Fig. 6.

Fig. 8 is a transverse section taken along the line 8—8 in Fig. 7.

Like numbers of reference refer to the same or similar parts throughout the several views.

Referring in detail to the drawing, there is shown an elongated straight blade having a flat straight handle 10 at one end and a flat point 11 at the other end which are joined by a filing section 12 which is reversely curved in a transverse direction as shown in Fig. 4. This filing section 12 includes a central concave filing section 13 and the two lateral concave filing sec-

tions 14 which converge slightly toward the tip 11.

The backs 15 and 16 of the filing sections 13 and 14 are smooth as are the edges 17.

It can be seen that in using this file, the finger nail will be confined to the grooves 13 or 14 formed by the filing surfaces. It is desirable to make the surfaces 13 and 14 of different grades of coarseness.

In using this file the nail will not be filed square across the edge but round, thereby eliminating the feather edge commonly produced.

Inasmuch as the surfaces 16 and 17 are smooth, it is clear that the skin cannot be injured during the filing operation.

In the modified form of the file shown in Figs. 5 to 8, inclusive, the handle 10—A is straight and the tip 11—A is separated from the fluted or undulating portion 12—B by a flat file section 12—B whose side 18 is cross cut up to the tip 11—A, while its side 19 has only the central portion 20 cut in continuation of the central grooved portion 13—A and preferably cut finer than the portions 13—A and the side 18 is cut finer than the grooves 14—A.

In this form of the device are combined all of the advantages of the old flat file and my new improved file as illustrated in Figs. 1 to 4, inclusive.

I claim:

A nail file comprising a flat straight blade having an undulating cross section between its ends, the concave areas of the undulating portions being file cut and the convex areas being smooth, characterized by having a flat tip end, said tip having a central file portion cut finer than is the central flute of said undulating portion and having its reverse side file cut across the entire side of the tip.

MAXWELL A. WEST.
